UNITED STATES PATENT OFFICE.

JASPER MEIN AND ALBERT MEIN, OF OSCEOLA TOWNSHIP, IOWA.

SNOW REMOVER FOR HIGHWAYS.

Application filed December 11, 1924. Serial No. 755,268.

To all whom it may concern:

Be it known that we, JASPER MEIN and ALBERT MEIN, citizens of the United States, residing at Osceola Township, in the county 5 of Franklin and State of Iowa, have invented certain new and useful Improvements in Snow Removers for Highways, of which the following is a specification.

Our invention relates to improvements in 10 snow removers for highways or other places, and the object of our improvement is to supply for this employment a simply constructed and relatively inexpensive device for propulsion by any desired means and for operation 15 of its moving mechanical parts by the same motor, to remove accumulated snow from roads and to discharge the same to the sides of the road out of the way of traffic.

This object we have accomplished by the 20 means which are hereinafter described and claimed, and which are illustrated in the accompanying drawings, it being understood that changes in the precise embodiment of invention herein disclosed can be made within 25 in the scope of what is claimed without departing from the spirit of the invention.

In the annexed drawings:

Fig. 1 is a front elevation of our snow remover, with a part of the snow discharger 30 shown in section. Fig. 2 is a view, partly in side elevation and partly in longitudinal vertical section, with parts broken away, of said snow remover as connected to and mounted on a tractor for both forward propulsion and operative action upon a snow bank. Fig. 3 is a rear elevation of the snow remover as separated from the tractor, and with parts in section or broken away.

Our device comprises snow removing and 40 discharging mechanism and means mounted on a rigid frame structure having connected frame parts or beams 1, 2 and 3 which support a backing 5 made of plank or metal, the latter forming also the rear part of the dischargers 9. Forwardly projecting beams 4 mounted on the vertical side beams or standards 2 carry triangular side closure plates 7 and a downwardly inclined metal plate top 6, this structure supplying at the bottom a forwardly projecting inclined prow 45 for the device. Other vertical or substantially vertical standards 10 have their lower ends pivotally mounted on the sides of said prow 6-7 on bolts 11, and have slots 12 to receive pins 13 on the prow, and secured by 50 nuts thereon to permit of forward swinging

of the standards. Arms 14 are pivoted at their rear ends to the upper part of the frame just below the mouths of the hollow dischargers 9 to project forwardly and having plates 15 mounted movably or slidably thereon. The plates 15 have longitudinal slots 16 to adjustably receive threaded pins 17 projecting from the arms and secured by 55 end nuts. The forward parts of the plates 15 are secured to the tops of said standards 10 and have apertured bearings registering with other apertured bearings in the standards to receive the end parts of a rotatable shaft 18, on each side, the inner end of each 60 short shaft 18 having a hub secured thereon with spider arms 20 inclosed in a circumferential ring 19. The spider spokes 20 are connected by means of the bars 21 which thus extend across the front of the upper 65 end of the device in spaced relation. The position of the shafts can be adjusted to somewhat lower the shafts 18 and set them 70 more forwardly by use of the adjusting means shown.

The use of the above described rotatable open wheel as it is rotated in the direction indicated by the arrow downwardly, is to thrust down and rearwardly the upper part 75 of a relatively high snow bank encountered to prevent the snow being forced over the top of the dischargers 9 where it would fill the air behind the device and interfere with the propulsion thereof by the following 80 tractor 44. It also delivers this top part of 85 the snow bank directly to the pair of rapidly rotating large delivery disks 51, insuring the complete reception by the device of the snow 90 ahead and its discharge through the funnels or open conduits 8-9 to opposite sides of 95 the device or the road.

The said snow wheel and the disks 51 are rotated simultaneously by the means now to be described. The device as a whole is propelled forwardly by some appropriate means 100 such as the tractor 44. To the crank-shaft of the motor of the tractor (not shown) prolonged forwardly in any desired way, is slidably connected a sleeve member 38 having a clutch-groove which receives the forks 105 39 of a lever of the bell-crank type medially pivoted at 40 and having its upper limb pivotally connected to the forward extremity of a connecting-rod 41. The rear end of this connecting-rod is pivotally connected to a 110 hand-lever 42 pivoted at its lower end to the tractor frame and having a manually

controllable detent for releasably engaging either of two notches on a rack-sector 43. By this means a cone-clutch member 37 may be shifted into or out of engagement with an internally coned friction member 36 non-slidably but rotatably mounted on the extension-shaft part 35 before referred to, the clutch-member 38 being non-rotatable on the shaft. Thus the bevel-gear 34 rigid with 10 said member 36 may be rotated in one direction.

Referring to Fig. 3, the numeral 33 denotes another bevel-gear in mesh with the gear 34 and mounted on a transverse counter-shaft 31. At each end of the shaft 31 mounted in bearings as at 32 are the sprocket-wheels 30 carrying the sprocket-chains 29 whose upper parts are passed about sprocket-wheels 28 mounted on short 20 shafts 26 in spaced bearing-boxes 27. On the shafts 26 are also mounted other like sprocket-wheels 25 carrying the lower parts of sprocket-chains 23 which latter are carried forwardly slopingly through 25 apertures 24 in the backing 5 to be mounted around the like sprocket-wheels which are mounted at 22 on the short shaft parts 18 of the snow-wheel 19. When the shaft 35 is rotated in the proper direction by the 30 tractor motor as is indicated in Fig. 3 by the arrow, the said driving connections act to rotate said snow-wheel in the direction of the arrow, that is, forwardly and downwardly to engage and draw the top of the 35 drift against the rotating disks 51.

The disks 51 are rotated in opposite directions and toward each other by the following driving connections.

Like bevel-gears 48 are mounted on the 40 shaft 31 on opposite sides of the middle gears 34 and 33 but in reversed positions, and intermesh with bevel-gears 49 on short shafts not shown mounted in bracketed bearing-boxes on the rear face of said backing plate 5. On the same shafts are mounted like sprocket-wheels 53 carrying the lower parts of sprocket-chains 54 whose upper parts are placed around sprocket-wheels 55 mounted on the shafts 50 which carry the said disks 51 before the backing-plate 5. It will be seen that the arrows indicate that the disks are by the said means rotated 50 reversely.

Referring to said Fig. 1, a smaller metal disk 52 is fastened by bolts upon the forward face of each disk 51 concentrically or coaxially and has integral radial raised and spaced ribs 53 providing seats for radially directed angle-bars 55 secured by bolts 54 to the disk 52, as also to the disk 51. The forwardly projecting flange 56 of each bar 55 is along its advancing edge and serves as a snow pusher and planer against the contacting face of a drift.

The snow remover frame may be rigidly

mounted on the tractor 44 in any desired way and by means of different connections. I have shown this frame carried on the front of the tractor rigidly by means of divergent bracket-bars 46 and 57 at each side, the 70 lower secured by bolts 47 to the frame standards and the upper bars secured to parts of the brackets 58.

In operation when the device is propelled 75 against a bank of snow, the prow 6 penetrates the drift immediately above the road surface, the oppositely rotating disks with their flanged blades 56 planing off thin 80 layers of the snow as guided by the prow and including snow pushed downwardly from the top of the bank against them by the snow-wheel 19 and its pushing bars 21. All the snow in front of the device is thus 85 broken up, gathered and delivered into the openings 8 of the dischargers 9, the snow being thrown from the latter to opposite sides of the device or of the road. As the quantity of snow cut and moved at any instant is relatively small, much power is 90 not required, and by this means the road can be quickly and completely cleared of snow accumulations. The scale of size may be 95 varied of the disks 51 and the other parts, so that a wide enough path can be made at one traverse for use by passing vehicles.

Having described our invention, what we claim as new and desire to secure by Letters Patent, is:

1. In a snow remover, in combination, a 100 transportable structure having a forwardly projecting inclined prow at its base, a pair of like wheels above the top of the rear of said prow rotatable reversely downwardly toward each other on longitudinal axes, a chute having a single opening into which both disks deliver medially, and a rotatable device with transverse horizontal blades supported swingingly adjustably above the forward upper parts of said disks to engage the tops of drifts and plane and propel thin 105 layers thereof downwardly toward the disks.

2. In a snow remover, in combination, a 110 transportable structure, snow-planing rotary devices mounted on its forward face, a chute having a mouth into which said devices both deliver, an adjustable rotatable fan-wheel with a plurality of longitudinal transversely arranged planer blades supported above and in advance of said devices to rotate in one direction in continuously 115 planing the top of a drift, delivering thereto and adjustable forwardly and vertically, and mechanism for simultaneously actuating said rotary devices and said fan-wheel.

3. In snow remover, in combination, a 120 transportable structure, snow-planing rotary devices mounted on its forward face to plane a transverse vertical face of a drift and drive the parts thereof 125

between them to a discharging device, a discharging device into which said devices deliver and which discharge to opposite sides of said structure, said structure having 5 a basal forwardly projecting inclined prow to direct snow toward said rotary devices, a forwardly and upwardly adjustable rotary fan device above and forward of said rotary devices having transverse horizontal blades

to plane the top of a drift, and to deliver 10 to both said first-mentioned snow-planing devices forward of their upper parts and connected coacting mechanisms for actuating said devices and fan.

In testimony whereof we affix our signatures. 15

JASPER MEIN.
ALBERT MEIN.
